UNITED STATES PATENT OFFICE.

WILLIAM HUGH FRASER, OF NEW YORK, N. Y.

SOUND-BOX ATTACHMENT.

1,358,719.

Specification of Letters Patent. Patented Nov. 16, 1920.

Application filed December 16, 1919. Serial No. 345,247.

To all whom it may concern:

Be it known that I, WILLIAM HUGH FRASER, a citizen of the United States, and a resident of New York, in the county of 5 New York and State of New York, have invented certain new and useful Improvements in Sound-Box Attachments, of which the following is a specification.

The present invention relates to improvements in sound reproducing devices of the 10 class commonly referred to as talking machines.

One of the objects of the invention is to provide the sound-box of a sound reproducing machine with a simple and efficient mechanism, in the form of an attachment, to modify the sound.

Another object of the invention is to so construct the sound-modifier that it can be 20 conveniently mounted upon sound-boxes and the sound-modifying member brought, at will, into operative or inoperative position.

A further object of the invention is to so construct the attachment that it serves at 25 the same time as a protecting means for the diaphragm of the sound-box.

With these and other objects in view, which will more fully appear as the nature of the invention is better understood, the 30 same consists in the combination, arrangement and construction of parts hereinafter described and pointed out in the appended claims and illustrated in the accompanying drawings, it being understood that many 35 changes may be made in the size and proportion of the several parts and details of construction within the scope of the appended claims, without departing from the spirit or sacrificing any of the advantages of the 40 invention.

One of the many possible embodiments of the invention is illustrated in the accompanying drawings, in which:—

Figure 1 represents a portion of a talking 45 machine, provided with a sound-box constructed in accordance with the present invention; Fig. 2 is a front elevation of the improved sound-box; Fig. 3 is a section taken on line 3—3 of Fig. 2; Fig. 4 is a section taken on line 4—4 of Fig. 3, on a 50 larger scale; Fig. 5 is a front elevation of the sound-modifying element of the attachment; and Fig. 6 is a perspective view 55 of a mechanism in engagement with the sound-modifying element.

In the drawings, the numeral 10 indicates a portion of the cabinet of a phonograph, on which is mounted in the well-known manner a rotating table 11, holding a tablet 12. With this tablet co-operates a stylus 60 13, held, for instance, by a screw 14 upon a support 15, that is fixed centrally to a diaphragm 16, the latter being mounted in the casing 17 of the sound-box. This sound-box is secured in any suitable manner to a 65 sound-arm 18, connected in the well-known manner with the cabinet 10. Thus far described, the construction and operation of the elements are well-known, so that a further detailed description of the same seems 70 to be unnecessary.

The sound-modifier includes a base plate 19, which is disposed in front of the diaphragm 16 and completely closes the sound-box, it being held upon the latter in any 75 suitable manner, for instance by spring clips 20, which are, preferably, made integral with the said base plate and engage a rim 21 upon the casing 17. The base plate is provided with a centrally disposed outwardly bulging portion 22, from which extends radially a slot 23, through which the stylus support 15 extends. In operative 80 relation to the diaphragm, there is disposed between the latter and the base plate 19 an 85 annular body 24, provided with a felt piece 25 on that face thereof which is juxtaposed to the said diaphragm. This annular body is provided with a radial slot 26 in alignment with the stylus support 15, so as to 90 permit a mounting of the attachment, as a whole, upon the sound-box. A plurality of pins 27 is provided upon the body 24, said pins being equidistantly disposed in a circle 95 on said body and extending at right angles to the plane thereof through the base plate 19. From the outer face of the base plate 19 projects a cylindrical casing 28, and through this casing extends a spindle 29, that is centrally and rotatably mounted in 100 the bulging portion 22 of the base plate 19. To this spindle is fixed a disk 30, having a plurality of cam faces 31. The number of these cam faces corresponds to the number of pins 27, each face projecting into a transverse slot 32 in a pin 27. The pin slots are disposed in the same plane, and the cam faces 31 are so shaped that a rotation in either direction of the disk 30 causes the sound-modifying member 24 to move at 110

right angles to the diaphragm and always remain in parallel relation thereto. Outside of the cylindrical casing 28, there is fixed to the spindle 29 a handle 33, having 5 a projection 34, that is adapted to be seated between any set of ridges 35 on the outer face of the casing 28. Of these ridges there are, in the case illustrated in the drawings, three pairs provided, they being marked in 10 their order by the numerals 0, 1 and 2.

The operation of the device is as follows:—The attachment may be placed, as a whole, upon the sound-box by engaging 15 the clips 20 thereof with the rim 21 on the said box. When in proper position, the base plate 19 of the attachment bears against the sound-box. When the handle 33 is in engagement with the ridges marked 0, the sound-modifying member 24 is disposed 20 at such a distance from the diaphragm that it does not affect the operation of the latter. By disengaging the handle from the ridges 0 and shifting said handle in the direction of the arrow shown in Fig. 2 of the drawings 25 until it engages the ridges 1, the sound-modifying member is brought nearer to the diaphragm of the sound-box, thereby decreasing the amplitude of vibration of the latter and consequently decreasing the loudness or intensity of the sound. By engaging 30 the handle 33 with the ridges marked 2, the sound-modifying member is forced against the diaphragm of the sound-box, whereby the amplitude of the vibration of the latter 35 is still more decreased, with a consequent decrease in the intensity of the sound.

It is to be observed that, while herein three stops for the handle have been shown, any other suitable number may be provided

to allow of greater variations of the intensity of the sound. Attention is also called to the fact that, while herein a specific shifting means for the sound-modifying member has been disclosed, others may just as well be provided without departing from 45 the invention, which lies mainly in the provision of a body for adjusting the amplitude of vibration of the diaphragm of the sound-box.

Attention is also called to the fact that 50 the attachment serves at the same time for protecting the diaphragm of the sound-box, by reason of its base plate 19 completely closing the sound-box.

What I claim is:—

- 55
1. The combination with the casing and diaphragm of a sound-box, of a frame fixed to said casing, a member shiftably disposed upon said frame in parallel relation to said diaphragm adapted to coact with the latter, 60 and a cam upon said frame in engagement with said member for varying, at will, the distance between said member and said diaphragm.
  2. The combination with the casing and 65 the diaphragm of a sound box, of a frame attached to said casing, a member shiftably disposed upon said frame in parallel relation to said diaphragm and adapted to coact with the latter, a plurality of pins fixed to 70 said member, and a cam acting upon said pins for varying, at will, the distance between said member and said diaphragm.

Signed at New York, in the county of New York and State of New York, this 3rd 75 day of December, 1919.

WILLIAM HUGH FRASER.
